(57) **CLAIM**

We claim the ornamental design for a basal attachment for thermometer, as shown and described.

DESCRIPTION

FIG. 1 is a perspective view of a basal attachment for a thermometer;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof; and,

FIG. 7 is a front elevational view thereof.

The broken lines are included for the purpose of illustrating portions of the basal attachment for thermometer and form no part of the claimed design.

1 Claim, 6 Drawing Sheets
